UNITED STATES PATENT OFFICE.

FELIX A. DE CANIO, OF WOODCLIFF, NEW JERSEY.

SHARPENING DEVICE.

Application filed January 22, 1926. Serial No. 82,917.

This invention relates to sharpening devices and is herein shown as particularly adapted to be used in resharpening razor blades.

5 The invention is characterized by the provision of a base or support with which is associated means for firmly anchoring the blade to be sharpened in such a position as to expose the cutting edge or edges there-
10 of to the action of a suitable sharpening instrument which is adapted to be moved longitudinally over the cutting edge or edges of the blade.

The general object of the invention is to
15 provide a simple, inexpensive, and effective device of the character mentioned.

Other objects and advantages of the invention will become apparent from the following description when taken in connection with the accompanying drawing in which—

Figure 1 is a perspective view of the device.

Figure 2 is a plan view of a sharpening instrument.

Figure 3 is a transverse sectional view through the device and showing the sharpening instrument so positioned as to be moved longitudinally over the cutting edges
30 of a razor blade.

A blade 5, herein shown as of a well known type, is adapted to be detachably connected to a base 6, while a sharpening instrument 7 is moved longitudinally over the cutting edges of the blade. The base 6 may be formed of wood or other suitable material and is provided with a central support 8. A pair of upstanding flanges 9 are carried by the base 6 and form with the support 8 a pair of channels 10.

The anchoring means for the blade 5 comprise a plate 16 suitably connected to the support 8 and located centrally and longitudinally thereof. The plate 16 is formed with a lip 17 adjacent one end thereof, and is provided with a pair of studs 18 which are received by the usual openings 20 formed in the type of razor blade herein shown. The lip 17 is slightly inclined with respect to the plate 16 and functions cooperatively with a keeper 21, to lock the blade upon the support 8, the keeper being pivotally connected to the opposite end of the plate 16 and adapted to be moved from its dotted line position, shown in Figure 1, to its full line position shown therein. The studs 18

which are received by the openings 20 in the blade 5 serve as a means for facilitating proper positioning of the blade 5 upon the support 8 so that the cutting edges of the 60 blade will be so exposed as to be acted upon by the sharpening instrument 7. These studs 18 also perform the important function of preventing lateral displacement of the blade once it has been anchored upon 65 the support.

In order that the blade 5 will assume a slightly curved contour when clamped in position upon the support 8, the support is formed with a groove 22 which is of a sufficient depth to so receive the blade anchoring means that the upper face of the plate 16 will lie somewhat below the parallel edges 15 of the support. By reason of such a relation between the bottom of the groove 22 and the upper face of the plate 16, the blade 5, when anchored to the support 8 is necessarily bowed, as shown in Figure 3, and its inherent resiliency is utilized to 75 keep the cutting edges of the blade in firm 80 contact with the edges 15 of the support.

The sharpening instrument 7 is constructed from suitable material, such as tempered steel, and is provided with diverging legs 24 which terminate in feet 25. These feet are inclined with respect to each other so as to engage the beveled margins of the blade adjacent the cutting edges thereof, and the ends of the feet are so finished as to conform to the parallel inner faces of the 90 flanges 9 which function as guides for the sharpening instrument 7 when the instrument is positioned as shown in Figure 3.

In order to provide a convenient means for giving to the blade a final sharpening or finish, a strip of leather 27 is suitably attached to the bottom of the base 6. This strip of leather 27 is preferably confined within a channel, as shown, between longitudinal ribs 28 formed integral with the 95 base 6 and projecting beyond the face of the leather.

To sharpen a razor blade, the blade is anchored to the support 8 as shown in Figure 1, whereupon the sharpening instrument 7 is 100 positioned as shown in Figure 3, so that the feet 25 of the instrument engage the edges 15 of the support 8. When the instrument is so positioned, it is moved backward and forward over the edges 15 of the support 8, the feet 25 riding over corresponding beveled faces of the blade adjacent opposite cut-

ting edges thereof. After a few strokes of the sharpening instrument 7, the blade 5 is removed and thereafter anchored in a reversed position so as to expose the other 5 beveled faces of the blade to the action of the sharpening instrument. Upon subjecting the blade to the second sharpening operation, the blade is removed, whereupon the cutting edges of the blade may be subjected 10 to a final stropping or sharpening by passing the blade over the strips of leather 27 secured to the opposite side of the base 6.

Having thus described certain embodiments of the invention what is claimed is:

- 15 1. A blade sharpening device comprising a support, means for detachably anchoring a blade to the top of said support with its cutting edge exposed, an upwardly projecting flange arranged longitudinally of said support, and a sharpening instrument adapted to be moved longitudinally over said cutting edge with its end abutting said flange as a guide for the instrument during such movement.
- 20 2. A sharpening device for double edge blades comprising a support, means for detachably connecting a double edge blade to said support so that the edges of the blade are exposed, and means arranged longitudinally of said support for guiding a sharpening instrument longitudinally over said support and the exposed edges of the blades.
- 25 3. A sharpening device for flexible blades comprising a centrally depressed support having edges against which opposite margins of the blade may be clamped, and means lying below the plane of said edges for anchoring a flexible blade to said support with its body portion curved and its cutting edges 30 exposed.
- 35 4. A sharpening device for flexible blades comprising a centrally depressed support having edges against which opposite margins of the blade may be clamped, and means lying below the plane of said edges for anchoring a flexible blade to said support with its body portion curved and its cutting edge exposed, and guiding means adapted to cooperate with said support for 40 guiding a sharpening instrument longitudinally over the cutting edge of the blade.
- 45 5. A blade sharpening device comprising a support upon which a blade to be sharpened is adapted to be anchored, a lug under

which one end of the blade is adapted to be 55 positioned, and a keeper adapted to be moved over the opposite end of the blade after its other end has been positioned under said lug, and means adapted to cooperate with said blade to facilitate central positioning of the same with respect to said support.

6. A blade sharpening device comprising a support upon which a blade to be sharpened is adapted to be anchored, a lug under 65 which one end of the blade is adapted to be positioned, and a keeper adapted to be moved over the opposite end of the blade after its other end has been positioned under said lug, and studs adapted to cooperate 70 with said blade to facilitate central positioning of said blade and to retain the same centrally positioned longitudinally of said support.

7. A blade sharpening device comprising 75 a support, a plate secured to said support, a lug carried by said plate under which one end of the blade to be sharpened is adapted to be positioned, and a keeper carried by said plate and adapted to be moved over the opposite end of the blade, said lug and said keeper cooperating to retain the blade in position upon said support.

8. A blade sharpening device comprising 80 a support, a plate secured to said support, a lug carried by said plate under which one end of the blade to be sharpened is adapted to be positioned, and a keeper carried by said plate and adapted to be moved over the 85 opposite end of the blade, said lug and said keeper cooperating to retain the blade in position upon said support, and studs carried by said plate and adapted to cooperate with said blade to retain the same against lateral movement with respect to said support.

9. A sharpener for double edge blades comprising a support having edges over which a sharpening instrument is adapted to be moved longitudinally of said support, and means for clamping a double edge blade longitudinally upon said support so that the edges of the blade are exposed to the action of the sharpening instrument as it is moved over said edges.

In testimony whereof, I have affixed my signature to this specification.

FELIX A. DE CANIO.
